Primary Examiner — Austin Murphy(74) *Attorney, Agent, or Firm* — Knobbe, Martens, Olson & Bear LLP(57) **CLAIM**

The ornamental design for a head mounted display visor, as shown and described.

DESCRIPTION

FIG. 1 is a rear perspective view of the head mounted display visor of the design.

FIG. 2 is a right side view thereof.

FIG. 3 is a left side view thereof.

FIG. 4 is a top plan view thereof.

FIG. 5 is a bottom plan view thereof.

FIG. 6 is a front elevation view thereof; and,

FIG. 7 is a rear elevation view thereof.

The broken lines in the drawings depict environmental structure and form no part of the claimed design.

1 Claim, 7 Drawing Sheets(56)
